UNITED STATES PATENT OFFICE.

ALBERT J. SCHNEIDER, OF DAYTON, OHIO.

DESIGN FOR A SMOKING STAND.

Application filed February 15, 1926. Serial No. 16,526. Term of patent 7 years.

To all whom it may concern:

Be it known that I, ALBERT J. SCHNEIDER, a citizen of the United States, residing at Dayton, Montgomery County, Ohio, have invented a new, original, and ornamental Design for a Smoking Stand, of which the following is a specification, reference being had to the accompanying drawing, forming a part hereof.

Figs. 1 and 2 are perspective views, from the side and front respectively, of a smoking stand showing my new design.

I claim:

The ornamental design for a smoking stand substantially as shown.

In testimony whereof I have hereunto set my hand this 12th day of February, A. D. 1926.

ALBERT J. SCHNEIDER.
